US0D1110193S

(12) **United States Design Patent** (10) **Patent No.:** **US D1,110,193 S**
(45) **Date of Patent:** **** Jan. 27, 2026**

(54) **FIGURINE**

(71) Applicant: **MONC DESIGN LTD.**, Netanya (IL)

(72) Inventor: **Mey Oren**, Hod Hasharon (IL)

(73) Assignee: **MONC DESIGN LTD.**, Netanya (IL)

(**) Term: **15 Years**

(21) Appl. No.: **29/945,263**

(22) Filed: **Jun. 2, 2024**

(51) LOC (15) Cl. **11-02**

(52) U.S. Cl.

USPC **D11/158**; D21/576; D21/604

(58) **Field of Classification Search**

USPC D11/131, 134–136, 157–160; D21/621, D21/604, 596, 610, 611, 616, 629, 653, D21/654, 655

CPC Y10S 362/806
